WINDOW SASH GUIDE ROLLER

Wayne S. Crumling, San Diego, Calif.
Application June 6, 1949, Serial No. 97,499

1 Claim. (Cl. 308—6)

My invention relates to a window sash guide roller, more particularly for reducing the friction of window sash in conventional window frames, and the objects of my invention are:

First, to provide a roller of this class which is very compact and readily installed in connection with window sash, for reducing the friction of the sash in a conventional window frame when forcing the same upwardly or downwardly therein;

Second, to provide a roller of this class which effectively prevents the diagonal binding of window sash in window frames when attempting to move the same upwardly or downwardly in the window frames;

Third, to provide a roller of this class having very simple bearing plates, which may be readily and easily connected to window sash without considerable alteration thereof;

Fourth, to provide a roller of this class having a maximum amount of bearing area in proportion to the cross-sectional area thereof;

Fifth, to provide a roller of this class having a maximum amount of window frame engaging area in proportion to the cross-sectional area thereof;

Sixth, to provide a roller of this class in which the bearing trunnions thereof are integral with the window frame engaging surface thereof, providing a very strong and durable roller structure; and

Seventh, to provide a window sash guide roller of this class which is very simple and economical of construction, efficient in operation, and which will not readily deteriorate or get out of order.

With these and other objects in view, as will appear hereinafter, my invention consists of certain novel features of construction, combination and arrangement of parts and portions, and certain modifications, as will be hereinafter described in detail and particularly set forth in the appended claims, reference being had to the accompanying drawings and to the characters of reference thereon, forming a part of this application, in which:

Fig. 1 is a side elevational view of a window frame and sash therein, showing portions of the window frame broken away and in section, and illustrating my sash guide rollers in connection with the sash movable within the frame; Fig. 2 is an enlarged side elevational view of my sash guide roller, showing a fragmentary portion of a window sash with which said guide roller is connected; Fig. 3 is an end elevational view of my sash guide roller, shown in connection with a window sash and engaging a window frame; Fig. 4 is a side elevational view of a modified form of my window sash guide roller, showing a portion thereof fragmentarily and illustrating a fragmentary portion of a window sash with which said guide roller is connected; Fig. 5 is an end elevational view of the structure, taken from the line 5—5 of Fig. 4; Fig. 6 is a side elevational view, showing another modified form of my window sash guide roller, and illustrating a fragmentary portion of the window sash with which said guide roller is connected; and Fig. 7 is an end view of the structure shown in Fig. 6, taken from the line 7—7 of Fig. 6.

Similar characters of reference refer to similar parts and portions throughout the several views of the drawings.

The bearing plate 1 and roller 2 constitute the principal parts and portions of my window sash guide roller, as shown in Figs. 1 to 3, inclusive, of the drawings.

The bearing plate 1, as shown in Fig. 2 of the drawings, is a substantially flat rectangular plate, having a central

opening 1a therein, and at opposite ends of this opening 1a are the offset arcuate bearing portions 1b, 1c, 1d and 1e. The offset bearing portions 1b and 1c are integral at each opposite side of the trunnion portions 2a of the roller 2. The bearing portion 1d is also integral at opposite sides of the trunnion portions 2a of the roller 2, while the bearing portion 1e terminates at its upper end 1f and is initially formed at substantially right angles to the plane of the plate 1a, so that the trunnions 2a of the roller 2 may be inserted in the bearing portions 1b and 1c and into engagement with the bearing portion 1d, whereupon the bearing portion 1e is then formed into position, whereupon the upper end 1f is in the position as shown in Fig. 3 of the drawings. It will be noted that the bearing portion 1e is formed at right angles near the location designated 1g, as shown in Fig. 3 of the drawings, preliminary to the insertion of the roller 2 into the bearing plate 1, all as shown best in Fig. 2 of the drawings.

The bearing plate 1 is provided with fixture receiving openings through which nails or screws 1h may be extended into the window sash for holding my sash guide roller thereon.

The operation of my sash guide roller is substantially as follows:

25 When installed as shown in Figs. 1 and 3 of the drawings, the four window frame bearing corners of the window sash, when moving upwardly and downwardly in the window frame, are laterally supported by the rollers 2, which engage the window frame, designated A, in

30 Figs. 1 and 3 of the drawings. Thus, frictional drag of the sash in the frame, and frictional binding or diagonal seizure of the sash in the frame, is effectively prevented. It will be here noted that the reduced diameter of the trunnions 2a in proportion to the larger diameter of the

35 middle portion of the roller 2, provides for the rotating action of said trunnions 2a in the bearing portions 1b, 1c, 1d and 1e, as hereinbefore described. It is to be noted that each roller 2 operates within a notch B in the edge of the sash A, as shown in Fig. 3 of the drawings, whereby rotating freedom of the roller 2 is unrestricted.

In the modified structure as shown in Figs. 4 and 5 of the drawings, the parts are designated as follows:

The bearing plates 3, 4, 5 and 6, and the roller 7 comprise the principal parts and portions of said modified

45 structure disclosed in Figs. 4 and 5.

The bearing plates 3, 4, 5 and 6 are all substantially identical in shape and general dimensions. Each of these bearing plates is provided with an offset arcuate bearing portion, substantially semi-circular in form, which is arranged to be positioned in opposed relationship with a similar offset bearing portion of an adjacent bearing plate for the engagement of one of the trunnions 7a of the roller 7, which is substantially identical to the roller 2 hereinbefore described. As shown in Fig. 5 of the drawings, the bearing plates 3 and 6 are arranged in contiguous relationship to each other, and the arcuate offset bearing portions 3a and 6a, in opposed relationship to each other, form a substantially circular bearing in which the trunnion 7a of the roller 7 is revolvably mounted.

55 60 Thus, the bearing for each end of the roller 7, at each trunnion portion 7a, is constructed by placing two of the substantially identical plates together, and these plates are provided with openings with nails 3b therein, as shown in Fig. 4 of the drawings, in which nails or screws may be used to secure said plates to the window sash, in a similar manner as hereinbefore described in connection with the structure disclosed in Figs. 2 and 3 of the drawings.

65 The operation of the modified structure shown in Figs. 4 and 5 of the drawings is similar to that as shown in Fig. 2 of the drawings, with the exception that the insertion of the roller 7 is facilitated by direct placement of the bearing portion of the bearing plates over the trunnions of the roller 7.

70 The modified structure, as shown in Figs. 6 and 7, is substantially similar to the structure shown in Figs. 2 and 3 of the drawings, and each of the bearing plates 8 and 9 is similar to the structure of the bearing plate 1, hereinbefore described, including the bearing portions 1c and 1b, which are arcuate opposed offset bearing portions. It is to be noted that the bearing plates 8 and 9

are substantially identical, and inasmuch as they are disconnected from each other, each may be readily positioned over its respective roller trunnion portion 10a of the roller 10, which is substantially identical in construction to the roller 2 hereinbefore described.

Though I have shown and described a particular construction, combination and arrangement of parts and portions, and certain modifications, I do not wish to be limited to this particular construction, combination and arrangement, but desire to include in the scope of my invention the construction, combination and arrangement substantially as set forth in the appended claim.

Having thus described my invention, what I claim as new and desire to secure by Letters Patent is:

In a window sash guide roller assembly, an elongated roller having integral reduced diameter trunnion portions at opposite ends, a pair of similar thin and substantially flat bearing plates, one of said plates being disposed at each end of said roller, each of said plates having integral therewith a pair of bearing portions aligned transversely 15 of the plate and each being substantially semicircular

in cross section and extending outwardly from opposite sides of the plate to define and constitute together a bearing for the corresponding trunnion portion.
